CORE BARREL

Lewis A. Larson and Arthur Soll, Compton, Calif.

Application February 18, 1935, Serial No. 7,023

17 Claims. (CL 255—72)

This invention relates to an improvement in core barrels of the type in which a plurality of core retaining tubes are telescopically mounted within the core barrel, said tubes being permitted to slide upwardly one at a time as the core enters the barrel.

An object of our invention is to provide a core barrel of the character stated, in which the circulating mud is prevented from contacting and washing the core after the core has entered the barrel.

Another object is to provide a core barrel of the character stated, in which the fluid in the upper part of the core chamber is released in a novel and effective manner.

Still another object is to provide a novel means of releasably engaging the core retaining tubes and releasing the tubes one at a time so that they may move upwardly as the core fills the same.

Still another object is to provide a novel means of suspending the core retaining chamber and the telescoping core tubes so that the chamber and the tubes can remain stationary while the outer barrel and the core bit rotates and moves into the formation.

Other objects, advantages and features of invention may appear from the accompanying drawings, the subjoined detailed description, and 30 the appended claims.

Figure 1 is a fragmentary longitudinal sectional view of the upper portion of the core barrel.

Figure 2 is a fragmentary longitudinal sectional view of the lower portion of the core barrel.

Figure 3 is a fragmentary longitudinal sectional view of the upper portion of the core retaining tubes and the hold-down means.

Figure 4 is a side elevation of the same.

Figure 5 is a fragmentary longitudinal sectional view of the core retaining tubes.

Figure 6 is a fragmentary side elevation of the lower end of one of the core retaining tubes.

Figure 7 is a fragmentary longitudinal sectional view of the core catcher and the lower end of the core retaining tubes.

Referring more particularly to the drawings, the numeral 1 indicates the outer barrel which is attached at its upper end to the drill pipe, in the usual and well known manner, this construction being so usual that it is not shown. A core bit 2 screws onto the lower end of the core barrel 1 for the purpose of cutting into the formation.

A protector barrel 3 screws into the core bit 2 and extends upwardly from this bit within the outer barrel 1. The protector barrel 3 is spaced

from the inner surface of the outer barrel 1 so as to provide a circulating passage 4. A plurality of circulation holes 5 are provided in the bit 2 thru which the circulating mud flows, for the usual purpose. A cup 6 screws onto the upper end of the protector barrel 3 for the purpose of preventing any circulating fluid from entering the top of the protector barrel and disturbing or washing away the core, as will be further described.

A core catcher ring 7 fits within a seat 8 in the core bit 2. The core catcher ring is thus rotatably mounted in the core bit so that the core-receiving portion of the barrel can remain stationary while the outer barrel and the bit 15 rotate and advance into the formation. A hold down barrel 9 screws onto the core catcher ring 7 and extends upwardly therefrom within the protector barrel 3. A head 10 screws onto the upper end of the hold down barrel 9, and suitable bearings 11 are mounted between the head and the protector barrel 3, for the purpose of suspending and rotatably mounting the hold down barrel within the core barrel. The hold down barrel 9 is spaced from the protector barrel 25 3, thus providing a fluid relief passage 12. This relief passage extends the full length of the hold down barrel 9, and a plurality of relief ports 13 are provided in the bit 2, said ports extending into the relief passage, thereby permitting the fluid—which accumulates in the relief passage—to flow out of the barrel.

The circulation holes 5 and the relief ports 13 may be so arranged that there is a syphoning action of the circulating mud passing thru the 35 circulation holes, thus tending to draw fluid out of the passage 12.

A plurality of relief ports 14 are provided at the upper end of the hold down barrel 9 and these ports extend into the passage 12, thus 40 permitting fluid to flow outwardly into the passage 12, and thence downwardly and out of the barrel thru the ports 13.

It will be evident from the foregoing description that the top of the protector barrel and the top of the hold down barrel are both closed, thus preventing any circulating fluid from entering the upper ends of these barrels to wash away the core which is entering the hold down barrel, 50 as is common in core barrels heretofore in use.

A plurality of core retaining tubes 15 are telescopically mounted within the hold down barrel 9. The tubes 15 rest on stepped seats 16 in the core catcher ring 7, the purpose of this 55

construction being to prevent circulating mud from entering around the bottom of the tubes and thence into the inner portion of the core barrel where the circulation mud would follow the core. The core retaining tubes 15 are slidably mounted and are adapted to move vertically within the next adjacent tube as the tube becomes filled with the core.

A sleeve 17 is mounted on the upper end of the innermost tube 15, and this sleeve is open at the top, as shown at 18. Thus, any fluid within the tubes 15 is forced upwardly thru 18 and thence out thru the ports 14 and the passage 12, as previously described.

15 As each successive tube 15 moves upwardly, the next adjacent tube is engaged and is carried upwardly by the following arrangement—a plurality of spring fingers 19 are mounted on the outside of each of the tubes 15 at the lower end thereof. These springs are counter-sunk into the tube so that when compressed, a smooth outer surface is presented.

A shoulder 20 is provided on the inner surface of each of the tubes adjacent the upper end. As 25 a tube reaches the top of its movement, the spring 19 springs outwardly and engages the shoulder 20. Continued upper movement of the innermost tube 15 will then drag the next adjacent outer tube along with it. Thus, each of the 30 tubes in succession is engaged and caused to move upwardly as the barrel fills with the core.

To disengage the tubes 15 each from the other, slots 21 are provided thru the shoulder 20 and the springs 19 can be rotated so as to align with 35 the slots, thus permitting the inner tube to slip upwardly out of engagement with the next adjacent tube.

A second safety shoulder 22 may be provided on the inside of each of the tubes 15 above the shoulder 20. The second shoulder also has slots 40 23 extending therethru to permit disassembly of the tubes.

To insure that each of the tubes will rise in proper order, i. e., that none of the outermost tubes 15 will move upwardly with the inner tubes, we provide a latch mechanism 24. This latch mechanism comprises a plurality of dogs 25 which are pivotally mounted in the hold down barrel 9, and these dogs are urged inwardly by 50 springs 26. The bottom surface of each of the dogs bears against the upper edges of the tubes 15 when the tubes are in lowered position, as shown in Figs. 1 and 3. The bottom of each of the dogs 25 is rounded so that as the innermost 55 tube rises, it will press the dog outwardly sufficiently to permit the tube to rise. Each successive tube will likewise engage the dogs as said tube starts to rise, will press the dog outwardly and continue its movement upwardly. The remaining tubes which are not in position to move upwardly, are held down by the dogs until the tube is engaged in the manner previously described.

If desired, the sleeve 17 may be provided with 65 an annular packing 27 which bears against the inner wall of the hold down barrel 9, thus preventing any fluid from flowing downwardly around outside of the sleeve.

Having described our invention, we claim:

70 1. In a core drill for well drilling operations, having a core bit at the bottom end, an outer barrel secured to the core bit and rising therefrom, a core retaining tube made of telescoping sections mounted within the outer barrel and 75 adapted to telescopically extend when and as a

core advances into the drill, and anti-friction means rotatably mounting the core retaining tube within the outer barrel.

2. In a core drill for well drilling operations, having a core bit at the bottom end, an outer barrel secured to the core bit and rising therefrom, a core retaining tube made of telescoping sections mounted within the outer barrel and adapted to telescopically extend when and as a core advances into the drill, and means releasably 10 engaging the telescoping sections whereby said sections are permitted to extend upwardly one at a time.

3. In a core drill for well drilling operations, having a core bit at the bottom end, an outer barrel secured to the core bit and rising therefrom, a core retaining tube made of telescoping sections mounted within the outer barrel and adapted to telescopically extend when and as a core advances into the drill, anti-friction means 20 rotatably mounting the core retaining tube within the outer barrel, and means releasably engaging the telescoping sections whereby said sections are permitted to extend upwardly one at a time.

4. In a core drill for well drilling operations, having a core bit at the bottom end, an outer barrel secured to the core bit and rising therefrom, a core retaining tube made of telescoping sections mounted within the outer barrel and 30 adapted to telescopically extend when and as a core advances into the drill, means releasably engaging the telescoping sections whereby said sections are permitted to extend upwardly one at a time, and inter-engaging means between adjacent telescoping sections whereby each section is successively engaged and caused to move upwardly as the adjacent inner section reaches the top of its movement.

5. In a core drill, an outer core barrel, a telescoping core tube extensibly mounted within the outer barrel and adapted to guide and hold a core as it advances into the core drill, and anti-friction means rotatably mounting the core tube within the outer barrel.

6. In a core drill, an outer core barrel, a telescoping core tube extensibly mounted within the outer barrel and adapted to guide and hold a core as it advances into the core drill, anti-friction means rotatably mounting the core tube 50 within the outer barrel, and means releasably engaging the telescoping sections whereby said sections are permitted to extend upwardly one at a time.

7. In a core drill for well drilling operations, having a core bit at the bottom end, an outer barrel secured to the core bit and rising therefrom, a core retaining tube made of telescoping sections mounted within the outer barrel and adapted to telescopically extend when and as a core advances into the drill, means releasably engaging the telescoping sections whereby said sections are permitted to extend upwardly one at a time, inter-engaging means between adjacent telescoping sections whereby each section is successively engaged and caused to move upwardly as the adjacent inner section reaches the top of its movement, and anti-friction means rotatably mounting the core tube within the outer barrel.

8. In a core drill, a hollow outer core barrel, telescopically mounted core tubes normally disposed in the lower end of the outer core barrel and adapted to telescopically follow any material entering the core drill, with the innermost of said 75

core tubes coming into contact with the entering core first, and succeeding sections following in the arranged order, and yieldable inter-connecting means between adjacent core tubes whereby the tubes are caused to move upwardly in order. 5

9. In a core drill, a hollow outer core barrel, telescopically mounted core tubes normally disposed in the lower end of the outer core barrel and adapted to telescopically follow any material 10 entering the core drill, with the innermost of said core tubes coming into contact with the entering core first, and succeeding sections following in the arranged order, inter-connecting means between adjacent core tubes whereby the tubes are caused to move upwardly in order, and releasable means engaging the core tubes adapted and arranged to release said tubes one at a time. 15

10. A core drill comprising an outer barrel, a core bit attached to the lower end of said barrel, a protector barrel attached to the core bit and rising within the outer barrel, a cap on the upper 20 end of the protector barrel, a core catcher ring seated in the core bit, a hold down barrel attached to the core ring catcher and rising within the protector barrel, said hold down barrel and protector barrel being spaced apart to provide a fluid 25 passage, said protector barrel having outlet openings in the top thereof, and said core bit having fluid relief holes extending into said passage and telescoping core tubes extensibly mounted 30 within the hold down barrel. 35

11. A core drill comprising an outer barrel, a core bit attached to the lower end of said barrel, a protector barrel attached to the core bit and rising within the outer barrel, a cap on the upper 40 end of the protector barrel, a core catcher ring seated in the core bit, a hold down barrel attached to the core ring catcher and rising within the protector barrel, said hold down barrel and protector barrel being spaced apart to provide a fluid 45 passage, said protector barrel having outlet openings in the top thereof, said core bit having fluid relief holes extending into said passage and telescoping core tubes extensibly mounted within the hold down barrel, a bearing arranged 50 between the hold down barrel and the protector barrel whereby the hold down barrel is guided and centered within the protector barrel. 55

12. A core drill comprising an outer barrel, a core bit attached to the lower end of said barrel, a protector barrel attached to the core bit and rising within the outer barrel, a cap on the upper 60 end of the protector barrel, a core catcher ring seated in the core bit, a hold down barrel attached to the core ring catcher and rising within the protector barrel, a plurality of extensible core 65 retaining tubes within the hold down barrel, and means releasably engaging said core retaining tubes whereby they are released one at a time. 70

13. A core drill comprising an outer barrel, a core bit attached to the lower end of said barrel, a protector barrel attached to the core bit and rising within the outer barrel, a cap on the upper 75 end of the protector barrel, a core catcher ring seated in the core bit, a hold down barrel attached to the core ring catcher and rising within the protector barrel, a plurality of extensible core 80 retaining tubes within the hold down barrel, means releasably engaging said core retaining tubes whereby they are released one at a time, and means releasably engaging said core retaining tubes whereby they are released one at a time. 85

means releasably engaging said core retaining tubes whereby they are released one at a time, and inter-engaging means between adjacent core retaining tubes whereby said tubes are successively engaged and moved upwardly as the core 90 enters the drill. 95

14. A core drill comprising an outer barrel, a core bit attached to the lower end of said barrel, a protector barrel attached to the core bit, and rising within the outer barrel, a cap on the upper 100 end of the protector barrel, a core catcher ring seated in the core bit, a hold down barrel attached to the core ring catcher and rising within the protector barrel, a plurality of extensible core 105 retaining tubes within the hold down barrel, a plurality of dogs pivotally mounted in the hold down barrel, spring means engaging each of the dogs whereby they are urged inwardly, said dogs bearing against the upper edges of the tubes and being adapted to be pushed outwardly as each 110 successive tube starts to move upwardly. 115

15. In a core drill comprising an outer barrel, a core bit attached to the lower end of the outer barrel, a protector barrel attached to the core bit and extending upwardly within the outer barrel, 25 a core catcher ring seated in the core bit, a hold down barrel attached to the core catcher ring and rising within the hold down barrel, a plurality of telescopically mounted core tubes within the hold down barrel, and stepped seats on the 30 core catcher ring upon which the core retaining tubes are adapted to rest when in lowered position. 35

16. In a core drill comprising an outer barrel, a core bit attached to the lower end of the outer 40 barrel, a protector barrel attached to the core bit and extending upwardly within the outer barrel, a core catcher ring seated in the core bit, a hold down barrel attached to the core catcher ring and rising within the hold down barrel, 45 a bearing between the hold down barrel and the protector barrel whereby the hold down barrel is centered and rotatably mounted within the protector barrel, a plurality of telescopically mounted core tubes within the protector barrel, and a sleeve attached to the upper end of the innermost of said core tubes. 50

17. In a core drill comprising an outer barrel, a core bit attached to the lower end of the outer barrel, a protector barrel attached to the core bit 55 and extending upwardly within the outer barrel, a core catcher ring seated in the core bit, a hold down barrel attached to the core catcher ring and rising within the hold down barrel, a bearing between the hold down barrel and the protector barrel whereby the hold down barrel is centered and rotatably mounted within the protector barrel, a plurality of telescopically mounted core tubes within the protector barrel, a sleeve attached to the upper end of the innermost of said 60 core tubes, said protector barrel and hold down barrel being spaced apart to provide a fluid passage, said hold down barrel having ports adjacent the upper end thereof and extending into said fluid passage, said core bit having fluid relief 65 holes extending into said fluid passage. 70
